(57) CLAIM

The ornamental design of a vacuum cleaner dirt receptacle lid, as shown and described.

DESCRIPTION

FIG. 1 is a top, front and left perspective view of a vacuum-cleaner dirt receptacle lid in the closed position showing our new design on a vacuum cleaner dirt receptacle;

FIG. 2 is a bottom, rear and right perspective view of a vacuum cleaner dirt receptacle lid in the open position on a vacuum cleaner dirt receptacle;

FIG. 3 is a top view of a vacuum cleaner dirt receptacle lid; and,

FIG. 4 is a bottom view thereof.

The vacuum cleaner dirt receptacle in FIG. 1 and FIG. 2 and the thumb tab extending from the vacuum cleaner dirt receptacle lid in FIGS. 1 to 4 are shown for illustrative purposes only and form no part of the claimed design.
